2,111,157

METHOD OF FORMING BOXES

John S. Stokes, Huntingdon Valley, Pa., assignor
to Stokes and Smith Company, Summerville,
Pa., a corporation of Pennsylvania

Application August 21, 1935, Serial No. 37,162
Renewed August 17, 1937

20 Claims.

(Cl. 93—43)

My invention relates to methods for forming and covering or staying boxes, containers, cartons or the like, hereinafter generically termed "boxes".

In accordance with my invention, a box blank adapted to form, for example, the bottom and one or more vertical walls of a box, is bent and substantially immediately registered upon two or more separate, spaced pieces of sheet material, such as components of a composite wrapper, tabbed, or untabbed, or tab strips preferably held flat by suction on a conveyor.

My invention further resides in the methods hereinafter described and claimed.

This application is a continuation-in-part of my copending application Serial No. 586,530, filed January 14, 1932 and upon which has issued Letters Patent No. 2,015,202.

For an understanding of my invention, reference is to be had to the accompanying drawings in which, in perspective:

Figure 1 illustrates the formation of assemblies each comprising the main component of a three-piece box and stay strips;

Fig. 2 illustrates the supply of box ends to a form block;

Figs. 3 and 4 illustrate the partially completed and completed box, respectively;

Fig. 5 illustrates the box of Fig. 4 with a wrap per applied;

Fig. 6 illustrates the formation of assemblies each comprising a one-piece box blank and stay strips or tabs;

Fig. 7 illustrates the formation of assemblies each comprising a one-piece box blank and short stay strips or tabs;

Fig. 8 illustrates the formation of assemblies each comprising a box blank and components of a four-piece wrapper;

Fig. 9 illustrates the partially completed box;

Figs. 10 and 11 show the completed box in upright and inverted position, respectively;

Fig. 12 shows the main component of a three-piece wrapper;

Fig. 13 shows the box made, using the wrapper component of Fig. 12;

Figs. 14 and 15 illustrate the use of stacks of box blanks, of the one-piece and three-piece types, respectively.

Referring to Fig. 1, the strip of box material removed from the roll R is scored lengthwise, as by knives 1, the distance between the scores being equal to the length or width of the box. For convenience of further explanation, it will be assumed that the distance between the scoring is

equal to the width of the box. The knives 4 sever the strip to complete formation of the blanks B1 each having a bottom panel Bb and side panels Bs.

After completion of one blank, the next blank, 5 completely formed except for the cutting operation, is brought into position for severance from the strip by knives 4 and, at the same time, the knives 4 score the parts of the strip subsequently to be formed into blanks.

Concurrently with the formation of the blanks B1 the tabs T1 are cut from the tab strips RT, as by knives 12, coated with adhesive, and delivered to the conveyor 5. The feeding, cutting and delivery of the tabs may be performed by mechanism shown in Rider Patent No, 1,806,181.

Preferably, as shown, the stay strips T1 are somewhat greater in length than the width of the blank B1. The strips with their adhesive-coated side on top, are transported in pairs by the suction conveyor 5 beneath the plunger 6.

The plunger, which may comprise a suction plate, engages the end blank B1, and after the knives 4, 4 are operated to sever it from the strip, the plunger moves downwardly passing 25 through an opening formed by the side folding slides 7, 7 which causes the side panels Bs to assume an upright position. Preferably, to avoid all possibility of the sides of the completed box being bowed, the panels are bent through an arc 30 substantially greater than 90° and for that purpose the slides 7, 7 move inwardly from the position shown to bend the panels nearly flat against the thin plate 6. For brevity, blanks so treated are hereinafter termed "bent".

The blanks are transferred by the plunger 6 through the bending stage exemplified by the slide 7 and deposited upon the tab strips T1, as indicated, leaving parts of the strips projecting beyond the sides and ends of the blank.

Preferably, at a point beyond the registering station, the side panels Bs of the blank or main box component are flattened against the tab strips T1 while still subject to suction.

The strips project beyond the sides of the blank or main component, so that at the box-forming station exemplified by form block 9, Fig. 2, these projecting tab portions may be folded into engagement with the box-end components BE which may be cut from a strip removed from rolls 50 RE. The tabs, when applied, hold the box walls or panels in box-forming position. A box-forming machine for supplying box-end components cut from strip material to a form block, such as form block 9 of Fig. 2, is described and claimed 55

in Rider et al, Patent No. 1,933,566. Since the tabs are preferably longer than the width of the main component, they have ends projecting above the top edges of the box at the corners, Fig. 3, which may be turned inwardly and downwardly, as shown in Fig. 4, to strengthen the corners of the box.

Specifically, in the method shown in Fig. 1, a strip of box material is fed step by step toward the bending station; the blanks cut from the strip are bent in succession and each in turn is transferred into registered adhesive engagement with a group of detached tabs, cut from the rolls RT and fed step by step by conveyor B toward the bending station. The conveyor 5 is at rest during the transfer of a blank into engagement with a group of tabs to form an assembly which thereafter is moved step by step by the conveyor toward the box-forming station. If desired, the blanks may be fed from a stack toward the bending station, as in subsequently described modifications.

It is to be noted that no wrapper is used, allowing a maximum of economy when the box is to serve as a shipping container, for example, or for other uses where wrapping for improved appearance is unnecessary. This method also affords economy of box material as the amount of cardboard used is no greater than the actual area of the box panels. There is no cardboard loss by corner notching of the box blanks or any overlapping of the cardboard.

If desired, the unwrapped stayed box of Fig. 4 may be covered. For example, the box F⁴ may again be passed through a wrapping machine and a wrapper applied thereto in the usual manner. The resulting box F^{4a}, shown in Fig. 5, is the same as that of Fig. 4 except that it is covered by a wrapper.

As shown in Fig. 6, the blanks, instead of each being the main component of a three-piece box, may be one-piece box blanks having a bottom panel B_b, side panels B_s, and end panels B_e. The blanks B may be fed in succession from the stack SB to the plunger 6 which transfers them in succession on to the successive pairs of tab strips T₁. Alternatively, the blanks may, as shown in Fig. 7, be cut from a strip of box material fed toward plunger 6.

Preferably, all of the panels are bent to avoid possibility of bowing of the sides of the completed box, and for that purpose the slides 7, 8, in succession or in pairs, move inwardly from the position shown to bend the panels nearly flat against the top of plunger 6.

Preferably, before the assembly leaves the conveyor surface, and while still subject to suction, at least the side panels of the box blank are pressed flat against the tab strips.

The blank with the tab strips adhering thereto is transported by the conveying surface 5 towards a box-forming station, for example, a box machine generally of the type shown in United States Letters Patent No. 1,541,255 to Federwitz et al., where the side and end panels of the blank are erected and the projecting portions of the tabs applied to hold them in box-forming position. Insofar as external appearance is concerned, the partially and fully completed box, using a one-piece blank, is the same as appears in Figs. 3 and 4, respectively. If desired, a wrapper may be subsequently applied, whereupon the completed box has the same appearance as the box of Fig. 5.

Particularly, when the box blank is of the one-

piece type, it is not always necessary that long tabs be used. As shown in Fig. 7, each of the box blanks B may be bent and registered upon a group of four short tabs each of which is substantially equal in length or preferably somewhat greater in length than the height of the box. These tabs are cut from the tab rolls RT, coated with adhesive, and delivered to the conveyor in groups of two pairs each. The mechanism disclosed in Rider Patent No. 1,806,181 is suitable for feeding, cutting and conveying groups of tabs in this manner.

In this modification, as in those previously described, the conveyor surface preferably moves intermittently in timed relation to the reciprocation of the suction plate, so that the box blank, whether it be a one-piece blank or the main component of a multi-piece blank, engages the tab strips while they are stationary. Further, it is preferable that the conveyor surface shall simultaneously carry more than one group of tabs and/or assemblies.

Before the assemblies are transported to a wrapping machine for completion of a box, it is desirable that the side panels of the blank be pressed downwardly to insure intimate engagement with the four associated tabs which, as indicated, project beyond the sides and preferably also beyond the ends of the blank. At the wrapping station the walls of the blank are erected in the usual manner and the projecting portions of the tabs applied to the end panels of the blank to hold them in box-forming position. Preferably, the tabs are sufficiently long to project to some extent above the upper edges of the box so that they may be turned inwardly and downwardly, as in Fig. 4.

Particularly, when it is intended that a wrapper is not to be applied, it is desirable also that the tabs should overlap to some extent the bottom panel of the blank to afford enhanced strength at the trihedral corners formed by the bottom side of the end panels. If desired, a wrapper may be subsequently applied to the stayed, unwrapped box by again passing it through a wrapping machine for application of a wrapper thereto in the usual manner.

The one-piece blanks, for use with short tabs, may be fed from a stack, as shown in Fig. 6, or may, as shown in Fig. 7, be cut from a strip of box material removed from the roll R.

In the latter case, as the strip of box material is fed towards the bending station, it is scored longitudinally, as by the knives 1, the distance between the scoring being, for example, substantially equal to the width of the bottom of the boxes to be formed. The knives 3, 3, operative while the strip is at rest, cut out the material at both edges of the strip between the side panels B_s and adjacent blanks B. The strip is preferably also scored transversely by scoring rolls 2, as indicated by the dotted lines x, x to define the end panels B_e of the adjacent blanks. The strip is subsequently severed as by knives 4 between the transverse scoring to form one-piece box blanks.

After completion of one blank, it is understood that the next blank completely formed, except for the final cutting operation, is brought into position for severance from the strip by knives 4 and, at the same time, or substantially concurrently, the scoring of portions of the strip subsequently to be formed into blanks is taking place; i. e., one-piece blanks are cut in succession from the strip, and at any given time there are sufficient blanks at various stages of completion.

Concurrently with the formation of the box blanks, the tab strips RT are cut to form groups of tabs T, as previously described.

The box blanks, are therefore, in succession cut from a strip and, in succession, bent and registered upon a group of detached tabs preferably held flat by suction in a registering position.

As in the preceding modifications, after each blank has been deposited upon a group of tabs to unite them, the conveyor again moves forward to bring another group of tabs into a registering position beneath the bending station for registering adhesive attachment of the next box blank and to move the assembly just formed from the assembly station toward the box-forming station.

Figs. 8 to 11 illustrate my method of forming a box from a one-piece blank and a four-piece wrapper. The box blanks are formed from a strip and transported to a bending station in the manner explained in connection with Fig. 7. Wrapper side panels WS are removed in pairs from the stacks Ss, coated with adhesive, as by their passage over roll 11 and transferred to the conveyor 5 which transports them in aligned spaced relation adjacent to the bending station.

Preferably, as the side panels are being coated with adhesive, there are deposited thereon at the portions of the panels adapted to overlie the corners of the completed box, the tabs t which are cut from the rolls RT of tab material by the knives 12.

While the conveyor is stationary with a pair of panels WS beneath the bending station, the suction plate, or transfer plunger 6 transports a blank B toward the conveyor, bending it as it passes the slides 7, 8, and deposits it upon the wrapper side panels which are, as indicated, so disposed that their adjacent portions m, s engage the bottom panel Bb of the box. Preferably, and as indicated, the side panels Bs of the box are, in this modification, pressed flat against the wrapper side panel while the assembly is still at the registering station, instead of subsequently, as in previously described modifications.

The wrapper end panels WE, removed from stacks Ss thereof, are fed, as by a conveyor 13, toward the delivery end of conveyor 5 in proper spaced relation, so that a box and wrapper assembly can be removed from conveyor 5 and deposited upon a pair of wrapper end panels WE to bring the four panels in their proper relative position to complete the assembly of the composite wrapper upon the blank.

The portions me, of the end panels WE, engage only the ends of the bottom panel Bb of the blank B so that, in effect, the box blank is in engagement with a wrapper which does not cover the bottom of the box.

The assemblies may be fed in succession by the conveyor 13 toward a wrapping station, specifically to the form block 9 of a wrapping machine, Fig. 9, where the projecting portions of the wrapper elements are applied to hold the erected box-walls in box-forming position.

In its upright position, the completed box F2, Fig. 10, looks the same as that of Fig. 5, but when the box is inverted, Fig. 11, it is seen that the bottom of the box is uncovered except along its edges which are covered by the narrow strips ms and me.

If, with this same general method, the wrapper component WI, Fig. 12, be substituted for the separate wrapper end panels WE, the box blank, as delivered to the wrapping machine form

block, has attached thereto a three-piece composite wrapper, having the bottom covering panel Wb and end-covering panels WE for covering the bottom of the box, as well as the sides and ends, to form a completely wrapped box F3, Fig. 13.

An advantage of both methods is that a great saving of paper is effected; in the method using the four-piece wrapper, the paper for covering the box bottom is saved, while with both the three and four-piece wrappers there is saved the paper otherwise wasted by corner notching.

As shown in Fig. 14, the box blanks B, in performance of the methods of Figs. 8 to 13, instead of being cut from strip, may be fed in succession from a stack SB to a transfer point 15 from which the plunger 6 moves them to and through a bending station into registering engagement with a pair of wrapper panels WS.

Great economy of both box material and paper can be effected by making the box in three pieces, 20 as previously described in connection with Fig. 1, and the wrapper of three or four pieces, as described in connection with Figs. 8 to 13. As indicated in Fig. 15, the blanks B1, adapted to form the bottom and sides of a box, may be fed in 25 succession from a stack to the transfer plunger 6 which passes then through the bending station into registering engagement with a pair of wrapper components WS.

While I have illustrated and described preferred methods, it is to be understood my invention is not limited thereto but is coextensive in scope with the appended claims.

What I claim is:

1. The method of making boxes which comprises feeding groups of detached elements of sheet material along a path to an assembly station, effecting registering adhesive engagement between box blanks with successive groups of said detached elements at the assembly station 40 to form assemblies, and transporting the assemblies in succession to a box-forming station and there completing the formation of boxes from said assemblies.

2. The method of making boxes which comprises feeding groups of detached elements of sheet material along a path to an assembly station, bending box blanks in succession, effecting registering engagement between the successively bent blanks with successive groups of said detached elements at the assembly station to form assemblies, and transporting the assemblies in succession to a box-forming station and there completing the formation of boxes from said assemblies.

3. The method of making stayed boxes which comprises feeding groups of detached tab strips along a path to an assembly station, effecting registering adhesive engagement between box blanks with successive groups of said detached tab strips at the assembly station to form assemblies, and transporting the assemblies in succession to a box-forming station and there forming and staying the boxes.

4. The method of making stayed boxes which comprises feeding groups of detached tab strips along a path to an assembly station, bending box blanks in succession, effecting registering adhesive engagement between the bent blanks with successive groups of said detached tab strips at the assembly station to form assemblies, and transporting the assemblies in succession to a box-forming station and there forming and staying the boxes.

5. The method of making stayed boxes which

- comprises feeding detached tab strips in pairs along a path to an assembly station, bending box blanks in succession, effecting registering adhesive engagement of the bent blanks at opposite ends of a panel thereof with successive pairs of said detached tab strips at the assembly station to form assemblies, and transporting the assemblies in succession to a box-forming station and there forming and staying the boxes.
10. 6. The method of making stayed boxes which comprises feeding detached tab strips in groups of two pairs along a path to an assembly station, bending box blanks, effecting registering adhesive engagement of the bent blanks at opposite ends of two panels thereof with successive groups of said detached tab strips at the assembly station to form assemblies, and transporting the assemblies in succession to a box-forming station and there forming and staying the boxes.
15. 7. The method of making and covering boxes which comprises feeding groups of detached wrapper components along a path to an assembly station, effecting registering adhesive engagement between box blanks with successive groups 20 of said detached wrapper components at the assembly station, and transporting the assemblies to a box forming and covering station and there forming and covering the boxes.
25. 8. The method of making boxes which comprises feeding groups of detached elements of sheet material along a path toward a box-forming station, feeding box blanks to a bending station adjacent said path in advance of said box-forming station, bending the blanks at said bending 30 station, and effecting adhesive registering engagement of the bent blanks with successive groups of said detached elements adjacent the bending station, and transporting the assemblies so formed to the box-forming station and there forming the boxes.
35. 9. The method of making stayed boxes which comprises feeding groups of detached tabs along a path toward a box-forming station, feeding box blanks to a bending station adjacent said path in advance of said box-forming station, bending the blanks at said bending station, and effecting adhesive registering engagement of the bent blanks with successive groups of said detached tabs adjacent the bending station, and transporting the assemblies so formed to the box-forming station and there staying the boxes.
40. 10. The method of making and covering boxes which comprises feeding groups of detached wrapper components along a path toward a box-forming and covering station, feeding box blanks to a bending station adjacent said path in advance of said first-named station, bending the blanks at said bending station, and effecting adhesive registering engagement of the bent blanks with successive groups of said detached wrapper components adjacent the bending station, and transporting the assemblies so formed to the box forming and covering station and there forming and covering the boxes.
45. 11. The method of staying and covering boxes which comprises feeding detached components of wrappers in groups along a path toward a box-covering station, tabbing the detached wrapper components at a station along said path, bending box blanks at a bending station adjacent said path in advance of said box-covering station and beyond the tabbing station, and effecting registering adhesive engagement of the bent blanks in succession with successive groups of detached tabbed wrapper components, and transporting
50. the assemblies so formed to the box-covering station and there staying the box blanks and covering the boxes.
55. 12. The method of making boxes which comprises feeding groups of detached elements of sheet material step by step along a path toward a box-forming station, intermittently feeding a strip of box material toward a bending station adjacent said path in advance of said box-forming station, severing said strip to form box blanks, bending the blanks in succession at said bending station, and effecting adhesive registering engagement of the successive bent blanks with successive groups of said detached elements adjacent said bending station, and transporting the assemblies so formed to the box-forming station and there forming the boxes.
60. 13. The method of making boxes which comprises feeding groups of detached elements of sheet material step by step along a path toward a box-forming station, feeding blanks in succession from a stack to a bending station adjacent said path in advance of said box-forming station, bending the blanks in succession at said bending station, and effecting adhesive registering engagement of the successive bent blanks with successive groups of said detached elements adjacent said bending station, and transporting the assemblies so formed to said box-forming station and there forming the boxes.
65. 14. The method of making stayed boxes which comprises feeding groups of detached tabs step by step along a path toward a box-forming station, intermittently feeding a strip of box material toward a bending station adjacent said path in advance of said box-forming station, severing said strip to form box blanks, bending the blanks in succession at said bending station, and effecting adhesive registering engagement of the successive bent blanks with successive groups of said tabs adjacent said bending station, and transporting the assemblies so formed to the box-forming station and there staying the box blanks in box-forming relation.
70. 15. The method of making stayed boxes which comprises feeding groups of detached tabs step by step along a path toward a box-forming station, feeding blanks in succession from a stack to a bending station adjacent said path in advance of said box-forming station, bending the blanks in succession at said bending station, and effecting adhesive registering engagement of the successive bent blanks with successive groups of said tabs adjacent said bending station, and transporting the assemblies so formed to said box-forming station and there staying the box blanks in box-forming relation.
75. 16. The method of making a box which comprises flattening a group of detached elements of sheet material upon a conveyor surface, moving a scored blank along a path into adhesive registering engagement with the group of said detached elements flattened on said surface, at a point in said path bending the blank at its scoring, and conveying the bent blanks and the attached elements of sheet material by said surface toward a box-forming station and there forming the boxes.
80. 17. In the operation of a box-forming system including a box-machine having a form block and a conveyor, the method which comprises feeding groups of detached elements of sheet material toward the box machine by said conveyor, supplying box blanks to a bending station adjacent the conveyor, transferring the box blanks

from the bending station each into registering adhesive attachment with a group of said detached elements to form an assembly, and transferring the assemblies from said conveyor to the 5 form block of said machine.

18. The method of making boxes which comprises feeding groups of detached elements of sheet material along a path to an assembly station, effecting registered adhesive engagement 10 between one-piece box blanks and successive groups of said detached elements at the assembly station to form assemblies, and transporting the assemblies in succession to a box-forming station and there completing the formation of boxes 15 from said assemblies.

19. The method of making boxes which comprises feeding elongated detached tabs in groups

of two along a path to an assembly station, effecting registered adhesive engagement of one-piece box blanks with successive groups of said elongated tabs at the assembly station to form assemblies, and transporting the assemblies so formed to a box-forming station and there completing application of the tabs to form stayed boxes. 5

20. The method of making boxes which comprises feeding detached tabs in groups of two pairs along a path to an assembly station, effecting registered adhesive engagement of one-piece box blanks with successive groups of said detached tabs at the assembly station to form assemblies, and transporting the assemblies to a box-forming station and there completing application of the tabs to form stayed boxes. 10 15

JOHN S. STOKES.
